ICE CREAM PACKAGE

Filed Nov. 27, 1928

Inventor:

R. R. Kennedy,

By *S. S. Kennedy*
Attorney.

UNITED STATES PATENT OFFICE

RIDGWAY R. KENNEDY, OF PHILADELPHIA, PENNSYLVANIA, ASSIGNOR TO ABBOTTS DAIRIES, INC., OF PHILADELPHIA, PENNSYLVANIA, A CORPORATION

ICE-CREAM PACKAGE

Application filed November 27, 1928. Serial No. 322,118.

My invention is a portable vendible package adapted for efficiently and safely refrigerating frozen confections by solidified gaseous refrigerant which, in absorbing heat, 5 gives off vapor developing considerable pressure in a tightly enclosed container.

My invention is designed to provide a simply made and readily assembled package consisting of one or more rectangular boxes containing a block or blocks of the confection and an outer container or receptacle, preferably cylindrical, housing the box or boxes and a refrigerant. The diameter of the inside of the outer container is preferably so 10 proportioned to the size of the inner boxes that passages of arcuate cross section are formed on all four sides of the boxes to permit free circulation of the refrigerant gas.

The joints of the outer container are normally sufficiently tight to prevent or minimize leakage of warm air into the package but sufficiently yielding to permit escape of gas generated from the refrigerant when the pressure within the package rises slightly above 20 atmospheric. The escaping refrigerant gas forms a layer of cold gas between inner and outer laminae of the outer container and checks ingress of warm air to the interior thereof.

30 A further object of my invention is the provision of a package of which either end may be treated as the bottom and the opposite end as a lid which may be removed without disturbing the refrigerant or confection within 35 the container.

In the preferred embodiment of my invention, a cylindrical carton of laminated faced corrugated board has telescoped on opposite ends thereof duplicate casings or closures consisting of flanged cylinders having therein yielding end disks formed of faced corrugated board, the number of disks being preferably greater than the number of laminations of the corrugated board in the cylinder. 40 When the ends of the carton are pressed against the disks, a close joint is normally formed preventing leakage of warm air into the package. When, however, the evolution of gas within the package raises the pressure 45 slightly above atmospheric, the end disks

yield slightly to the pressure, thereby unseating them from the edges of the carton and opening the joints so that gas escapes outwardly and passes between the outer wall of the carton and the inner walls of the external casings. The edges of the external casings are preferably slightly spaced from one another at the middle of the package to permit escape of gas. 55

The characteristic features and advantages 60 of my improvements will more fully appear from the following description and the accompanying drawings in illustration of a preferred embodiment thereof.

In the drawings, Fig. 1 is a broken perspective view of an ice cream package embodying my improvements; Fig. 2 is a longitudinal sectional view thereof on a reduced scale; and Fig. 3 is a transverse sectional view 65 taken on the line 3—3 of Fig. 2. 70

As illustrated in the drawings, the cylindrical casings 1, preferably rolled from paper board, have fixed to the edges thereof the reinforcing flanges 2 forming seats for disks 3 of faced corrugated paper. The peripheries of the disks 3 fit closely in the casings 1 75 so as to form tight joints therewith.

A cylindrical carton 4, preferably wound from a plurality of laminations of faced corrugated paper fastened along a longitudinal joint, as by rivets, staples or adhesive, is telescoped within and makes a close fit with one of the casings 1. The edge of the carton 4 normally closely abuts against the upper disk 3 in the telescoped casing. A refrigerant 6, such as solidified carbon dioxide gas, is placed 80 in the carton and bricks of ice cream contained in square boxes 7 are deposited on the refrigerant. A second block of refrigerant 6 is placed on top of the ice cream boxes and the container is closed by telescoping the second casing 1, containing disks 3, over the open end of the carton. As will be observed from 85 Fig. 3, the sides of the ice cream boxes are surrounded by passages of arcuate cross section permitting free circulation of refrigerant gases. 90

When the package is originally closed, the edges of the carton 1 make close contact with the surfaces of disks 3 and prevent ingress of 100

warm air into the package. When, however, carbon dioxide gas begins to form, the pressure of the gas unseats the yielding disks from the edges of the carton 1. The gas is thus permitted to escape between the walls of the cylinders 1 and 4, the former being preferably made of unyielding material and the latter of yielding material. The gas passes out through the narrow mouth 8 between the edges of the disks 1.

10 Having described my invention, I claim:

1. A frozen confection package consisting of cylindrical casings telescoped upon a carton of corrugated sheet material, said carton having its ends covered by disks seated in said casings, and a rectangular confection box housed within said carton and having its sides surrounded by refrigerant circulating passages of arcuate cross section.

2. A package for a gaseous refrigerant and food product comprising a cylinder of corrugated sheet material having open ends, casings telescoping over opposite ends of said cylinder and having therein disks of corrugated sheet material yieldingly sealing the ends of said cylinder.

3. A package for a gaseous refrigerant and a food product consisting of an open ended carton of insulating sheet material, closures of yielding insulating material engaging the ends of said cartoon, and a flanged casing telescoped over each end of said carton and having their inner edges slightly spaced from one another when fully telescoped on said carton.

35 4. A frozen confection package consisting of similar cylindrical casings telescoped upon opposite ends of a carton of corrugated sheet material, corrugated paper disks seated in said casings against the edges of said carton, solidified gaseous refrigerants at opposite ends of said carton, and a rectangular confection box within said carton between said refrigerants.

45 In testimony whereof I have hereunto set my hand this seventh day of November, 1928.

R. R. KENNEDY.
